UNITED STATES PATENT OFFICE.

HENRY HOWARD FREER, OF LEICESTER, ENGLAND.

CUTTING MACHINE.

1,419,037.

Specification of Letters Patent. Patented June 6, 1922.

Application filed September 1, 1921. Serial No. 497,578.

(GRANTED UNDER THE PROVISIONS OF THE ACT OF MARCH 3, 1921, 41 STAT. L., 1313.)

To all whom it may concern:

Be it known that I, HENRY HOWARD FREER, a subject of the King of England, residing in Leicester, England, have invented certain new and useful Improvements in Cutting Machines, for which I have filed application in Great Britain on the 12th May, 1920, No. 13,183, and of which the following is a specification.

10 This invention is for improvements in or relating to cutting-machines in which one or more layers of material, for example tanned hides, have shaped portions cut from them by means of a cutting-tool pressed 15 through the one or more layers of material.

The type of machine to which this invention relates is that in which the cutting-tool is operated by a vertically reciprocating knife press which is also capable of 20 bodily movement in a horizontal plane in relation to the support for the material to be cut, power driven mechanism being provided to effect the vertical reciprocation and horizontal movement aforesaid.

25 It has previously been proposed to employ in machines of this type a knife press mounted to swing in a circular arc over the surface of a fixed support and to provide means for automatically actuating the press 30 so that it first swings to a predetermined position over the support surface, delivers its pressure-applying stroke and then returns to its initial or to an inoperative position. In this case the means for determining the 35 operative position over the support to which the press would swing comprised a control member which required to be first moved by hand into the predetermined position which it was desired the press should take up in 40 relation to the support.

The object of the present invention is to provide an improved machine of the aforementioned type in which the material, after it has been secured on the support, may be 45 cut into shaped portions from any desired part of the material.

According to the present invention a cutting-machine of the type described is characterized by the knife-press aforesaid being 50 mounted for rectilinear movement over the surface of the support, and by a plurality of separate individually manually-operable selective means operatively connected with the power-transmission mechanism to deter-

mine the position to which the press shall 55 travel in relation to the support, effect the cutting operation and thereafter return the press to its position of rest.

The particular manner in which the invention is carried into effect will be more 60 clearly understood from the following description of one preferred form of the invention given by way of example with the aid of the accompanying drawings in which—

65 Figure 1 is a top plan of the machine part of the support being removed to show certain portions of the power-transmission mechanism;

Figure 2 is a side elevation of Figure 1;

70 Figure 3 shows on an enlarged scale a portion of one of the selective devices;

Figure 4 is a section on the line IV—IV of Figure 3.

75 Figure 5 is a detail on an enlarged scale of the adjusting mechanism of the height of the knife-press; and

80 Figures 6 and 7 are perspective views of details of the power-transmission mechanism.

Like reference numerals indicate like parts throughout the several figures of the drawings.

A fixed support or table 1 for material to be cut is supported at the upper end of hollow standards 2.

85 A shaft 3, journaled in bearings in the standards 2, has cams 4 which are secured to the shaft to rotate with it and which engage the lower ends of reciprocating members 5 guided in the standards 2. At their upper ends each of the members 5 is connected with a cross-beam 6 extending transversely across the table, as shown in Figure 1, and the cross-beams 6 support, by their 90 opposite ends, guide-frames 7.

95 Running in channels in the guide-frames 7 are rollers 8 carried in the lower ends of supports 9, one for each corner of a knife-press 10, which is in the form of a flat plate, 100 and has knives secured to it in any preferred manner so that they project downwardly from the under surface of the plate. The press 10 is adjustable as to its height on the supports 9 in the manner shown particularly in Figures 1, 2 and 5, and for the purpose of accommodating the press to any depth of knife which it may be desired to

employ. The upper end of each support 9 is screw-threaded as at 11 to engage with a correspondingly-threaded sleeve 12, which is, at its upper end, formed as a sprocket 13. 5 Each sleeve 12 is secured within the press 10 so as to be free to rotate therein but to be held against endwise movement by means of a shoulder 14 and a nut 15. Passing round all the sprockets 13 is a chain 16 which passes 10 over a central sprocket 17 mounted on a spindle 18 carrying a hand-wheel 19. Thus movement of the hand-wheel 19 will effect rotation of each of the sprockets 13 thereby 15 to adjust the height of the press 10 equally on each of the four supports 9.

Carried in bearings 20 secured at intervals along the length of one side of the support 1, is a rod 21 and, as shown particularly in Figures 1, 2 and 3, the rod is furnished with a number of manually-operable devices 22. Each device 22 comprises a sleeve mounted for rotation on the rod 21 but held from endwise movement thereon by means of a pin 23 secured to the rod and engaging within a segmental slot 70 cut through the sleeve 22. One end of each sleeve 22 is guided to slide in the left-hand member of the bearing 20, as shown in Figure 3, and each of the sleeves is formed with 25 an abutment 24 which also constitutes a handle by which it may be manually operated.

In conjunction with each device 22 is a member 25 secured to, or formed as, a flange 35 on the rod 21 and having cut on its periphery 2 ratchet-teeth 26. One or the other of these teeth is engaged by a pawl 27 pivoted at 28 in one of the bearing-members 20.

Each of the selective devices is similarly 40 constructed so that a description of one serves for all, and it will be seen that by the provision of the slots within which the pins 23 are engaged, any one of the devices can be turned upwardly from its position shown in 45 Figures 2 and 3 to move with it the rod 21 without, however, moving the other selective devices. By the expression "turned upwardly" is meant that the abutment 24 can be moved from the position shown in Figure 50 3 to a substantially horizontal position in which it will extend outwardly from the plane of the paper. In this latter position it will be disposed in the path of an abutment 29 on one of the supports 9 of the 55 press.

At its end remote from the normal position of the press, shown in Figures 1 and 2, the rod 21 is pivotally connected to a lever 30 which rocks about a pivot 31 supported 60 in a fixed bracket on one of the standards 2 and engaging at its other end at 32 with the operating mechanism of a one-revolution clutch shown generally at 33. The clutch 33 is such that when it is operated it will cause 65 a single revolution only of the shaft 3,

whereafter it will automatically become disengaged. Such clutches are well-known and need no detailed description.

A transverse shaft 34, rotatably mounted in bearings in a bracket 35, has at its opposite ends pulleys 65 connected by driving bands 66 as shown in Figures 1 and 2 with the knife-press. Thus, rotation of the shaft 34 in one direction will draw the knife-press across the table from right to left, while 70 rotation in the reverse direction will return the press in the opposite direction. Freely rotatable on the shaft 34 are two dog-clutch elements 36 and 37, the co-operating members of which clutches respectively are shown 75 at 38 and 39. These latter elements are free to slide on the shaft 34 but are keyed to rotate with it. The clutch-parts 36 and 37 are rotatably connected to pulleys 40 and 41 respectively which are belt-connected as at 80 42 and 43 (Figure 2) to a power-shaft 44. It will be seen that of the belts 42 and 43 one is directly connected and the other is cross-connected to the clutch-pulleys so that the latter will rotate in opposite directions. 85

As shown in detail in Figure 6, the rod 21 has an arm 45 connected by means of a rod 46 to a bell crank lever having arms 47 and 48 and pivotally mounted at 49 in the bracket 35. A rod 50 connects the arm 48 with the 90 clutch-member 38.

The clutch-member 39, as shown particularly in Figure 1 is operated by one arm 51 of a bell-crank lever, the other arm 52 of which is connected with a rod 53 (see 100 Figure 7) to an arm 54 at the upper end of a spindle 55 carried in bearings 56 on one of the standards 2. At its lower end the spindle 55 has an arm 57 carrying a roller 58 which engages with a cam 59 secured to 105 the shaft 3.

Another arm 60 at the upper end of the spindle 55 is pivotally connected by a rod 61 to a lever 62 which is pivoted at its lower end at 63 in a bracket 64 on one of the standards 2. The upper end of the lever 62 extends, as shown in Figure 2, in the path of the press 10.

Co-operating with the shaft 21 is a helical spring 67 normally tending to resist rotational movement imparted to the rod by the selective devices and also tending to resist endwise movement of the rod 21. 115

The operation of the machine is as follows:—

The material to be cut is secured to the top of the support 1. It is then determined from what part of the material the required shapes are to be cut and the particular selective device corresponding to that portion of the material determined upon is operated by moving the abutment 24 upwardly as described. This has the effect of moving the abutment 24 into the path of the abutment 29 and at the same time rotating the shaft 130

21 which, through the mechanism illustrated in detail in Figure 6, throws the clutch-member 38 into engagement with the clutch-member 36. The shaft is held in this adjusted position by the pawl 27 engaging behind one of the teeth 26 on the part 25. The shaft 34 is thus caused to rotate so that the pulleys 65 and driving bands 66 draw the press towards the left of Figures 1 and 2 until the abutment 29 strikes the abutment 24. The engagement of the abutments 24 and 29 also effects endwise movement of the rod 21 which releases the pawl 27 from the ratchet-tooth 26 to allow the shaft to be rotated by the spring 67 in the direction opposite to that in which it was rotated by the selective device. Thus, the clutch-parts 36 and 38 are disengaged, thereby stopping the travel of the press. At the same time the endwise movement of the rod 21 throws into operation the one-revolution clutch 33 whereby the shaft 3 is rotated and, by means of the cams 4 and members 5, the frames 7 are moved downwardly to force a cutting-knife, separate from or integral with the press, through the material. The drive, operating in conjunction with the clutch 33, may be connected with a pulley 69 loosely mounted on the shaft 3 but the driving-belt for this purpose, and its connection with the power-shaft, is not shown. At the end of the cutting-operation the cam 59 comes into operation to press against the roller 58 to turn the rod 55 and through the parts 53, 52, 51 to engage the clutch-parts 37, 39. This engagement causes the shaft 34 to rotate to return the press to the right of Figures 1 and 2 and towards the end of its travel in this direction the press engages the upper end of the lever 62, which, operating through the parts 61 and 60, turns the spindle 55 to disengage the clutch-parts 37, 39. Thus, the complete cycle of operations is effected, at the end of which the press is returned to its position of rest.

Thereafter any other one of the selective devices can be utilized to bring the press over another desired portion of the material to be cut and to effect a cutting-operation from the newly-selected portion.

It will be obvious that details of the mechanism may be modified in many ways to effect a similar cycle of operations without departing from the spirit of the invention.

What I claim as my invention and desire to secure by Letters Patent is:—

1. A cutting machine comprising in combination a substantially horizontal support for the material to be cut, a knife press, means to reciprocate said press vertically over the support, means to impart rectilinear movement to the press along the support, selective mechanism manually operable to control automatically and in sequence the horizontal movement of the press up to one of a plurality of predetermined positions over the support, then the vertical reciprocation of the press to effect the cutting stroke, and subsequently the return of the press to its initial position on completion of said stroke, substantially as described.

2. A cutting machine comprising in combination a substantially horizontal support for the material to be cut, a knife press, means to reciprocate said press vertically over the support, means to impart rectilinear movement to the press along the support, a plurality of separate selective devices each of which is individually operable to control automatically and in sequence the horizontal movement of the press up to one of a plurality of predetermined positions over the support corresponding respectively to the aforesaid selective devices, followed by the vertical reciprocation of the press to effect the cutting stroke, and by the return of the press to its initial position on completion of said stroke, substantially as described.

3. A cutting machine comprising in combination a substantially horizontal support for the material to be cut, a knife press, means to reciprocate said press vertically over the support, means to impart rectilinear movement to the press along the support, a plurality of selective devices each manually operable to control the movement of the press to a different position along the support, a control member actuated by said selective devices to effect the vertical cutting stroke of the press, and means automatically operable on completion of the cutting stroke to return the press to its starting position, substantially as described.

4. A cutting machine comprising in combination a substantially horizontal support for the material to be cut, a knife press mounted for vertical reciprocation over the support and for translation along the support, power-transmission mechanism to impart the reciprocating and translatory movements to the press, a control member extending in the direction of the length of the support, rotatable about a fixed axis to couple the traversing drive of the press to the power-transmission mechanism, and movable endwise in the direction of that axis to couple the reciprocating drive of the press to said power mechanism, a plurality of selective devices spaced apart along the length of the control member and each movable independently of the others to rotate the control member, an abutment on each selective device which, on rotation of the latter is brought into the path traversed by a part of the knife press, means automatically operable on completion of the cutting stroke of the press to reverse the traversing drive thereof, and means to disconnect said traversing drive when the press

115

120

125

130

reaches its starting position, substantially as described.

5. A cutting machine comprising in combination a substantially horizontal support for the material to be cut, a knife press mounted for vertical reciprocation over the support and for translation along the support, power-transmission mechanism to impart the reciprocating and translatory movements to the press, a control member extending in the direction of the length of the support and mounted for rotation about a fixed axis and for endwise movement in the direction of that axis, resilient movement to resist the rotation and endwise movement of the control member, a plurality of selective devices spaced apart along the control member and each movable independently of the others to rotate said member, a clutch device operated by the rotation of the control member to couple the power-transmission mechanism to the traversing drive of the press, an abutment on each selective device adapted on rotation of the latter to be brought into the path traversed by a part of the press, means operated by endwise movement of the control member to disconnect the aforesaid traversing drive, a one-revolution clutch operated on endwise movement of the control member to couple the power-transmission mechanism to the reciprocating press drive, means automatically actuated on completion of the cutting stroke to couple the traversing drive through a reverse gear with the power transmission mechanism, and means operated by the press on reaching its starting position to disconnect said traversing drive, substantially as described.
- 40 6. A cutting machine comprising in combination a substantially horizontal support for the material to be cut, a knife press mounted for vertical reciprocation over the support and for translation along the support, power-transmission mechanism to impart the reciprocating and translatory movements to the press, a control member extending in the direction of the length of the support, rotatable about a fixed axis to couple the traversing drive of the press to the power-transmission mechanism, and movable endwise in the direction of that axis to couple the reciprocating drive of the press to said power mechanism, spring means to oppose rotation and endwise movement of the control member, a plurality of selective devices mounted at intervals along the control member, each device being free to rotate in one direction on said member but held against endwise movement thereon, an abutment on each selective device which on rotation

of the latter is adapted to be brought into the path traversed by a part of the press, a pawl and ratchet device to prevent backward rotation of the control member under the turning effort of its spring, means to release said pawl and ratchet when the control member is moved endwise, means automatically operable on completion of the cutting stroke of the press to reverse the traversing drive of the press, and means to disconnect said traversing drive when the press reaches its starting position, substantially as described.

7. A cutting machine comprising in combination a substantially horizontal support for the material to be cut, a substantially horizontal frame extending along the support and adapted to be reciprocated vertically, a knife press mounted for reciprocation by said frame and guided therein for horizontal movement along it and over the surface of the support, power-transmission mechanism to reciprocate the frame and impart translation to the press along the frame, a control member extending in the direction of the length of the support at one side thereof and mounted for rotation about a fixed axis and for endwise movement in the direction of that axis, spring means to oppose rotation and endwise movement of the control member, a plurality of selective devices mounted at intervals along the control member, each device being free to rotate in one direction on said member but held against endwise movement thereon, a clutch device operated by rotation of the control member to couple the power-transmission mechanism to the traversing drive of the press, a pawl and ratchet device to maintain the control member against the turning effort of its spring in the position to which it is moved by rotation of a selective device, an abutment on each selective device which on rotation of the latter is brought into the path traversed by a part of the press, means to release said pawl and ratchet when the control member is moved endwise, a one-revolution clutch operated by endwise movement of the control member to couple the power-transmission mechanism to the reciprocating drive of the press, means automatically actuated on the completion of the cutting stroke to couple the power-transmission mechanism through a reverse gear with the traversing drive of the press, and means operated by the press on reaching its starting position to disconnect said traversing drive, substantially as described.

In testimony whereof I affix my signature.

HENRY HOWARD FREER.
